UNITED STATES PATENT OFFICE.

ROBERT KONTEZKY, OF ROCHESTER, NEW YORK.

WORK-SUPPORT FOR SHOE-NAILING MACHINES.

1,398,557.

Specification of Letters Patent. Patented Nov. 29, 1921.

Application filed October 27, 1920. Serial No. 420,040.

To all whom it may concern:

Be it known that I, ROBERT KONTEZKY, a citizen of the Republic of Germany, residing at Rochester, in the county of Monroe 5 and State of New York, have invented certain new and useful Improvements in Work-Supports for Shoe-Nailing Machines, of which the following is a specification.

The object of this invention is to provide 10 a new and improved form of work support for use in connection with shoe nailing machines.

This and other objects of this invention will be fully illustrated in the drawing, described in the specification and pointed out 15 in the claims at the end thereof.

In the accompanying drawing:

Figure 1 is a side elevation of a portion of a shoe nailing machine with my work 20 support provided thereon.

Fig. 2 is a detail perspective view of the work support.

Fig. 3 is a horizontal sectional view 25 through a portion of the support and the part of the machine to which it is fastened, the section being taken on the line 3^x-3^x of Fig. 1.

Fig. 4 is a vertical sectional view of the bearing of the work support, the section 30 being taken on the line 4^x-4^x of Fig. 3.

In the several figures of the drawing, like reference numerals indicate like parts.

In the drawing, reference numeral 1 indicates the base and upright of the nailing 35 machine for which the work support forming the subject matter of the present invention is adapted. The upright 1 has a short vertical projection 2 formed thereon in which the standard 3 is mounted. A sleeve 4 is mounted to slide on the standard 3 and is raised and lowered thereon by means of the pinion 5, mounted on the second sleeve 6, located below the sleeve 4. The pinion 40 5 meshes with the rack 7 cut into one side 45 of the standard 3 and provided on the outside of the sleeve 6.

The sleeve 4 has the sleeve 9 formed integrally therewith and parallel thereto, in which the work support proper is mounted. 50 This work support comprises the shank 10 having a fork 11 formed on the lower end thereof. The shank 10 is provided with a series of holes 12 placed in a vertical row one on top of the other. A pin 13 is adapted 55 to engage into one of these holes and rest on the upper edge of the sleeve 9 in

order to hold the shank in the desired elevation on the machine. The holes 12 allow for vertical adjustment of the work support in the sleeve 9 in that the pin 13 may 60 be placed into any one of the holes 12.

The fork 11 of the work support is formed by the depending arms 14 and 15, the lower ends of which are curved outwardly to provide bearings for the shaft 16 to be mounted therein. The rear of the fork 11 with its arms 14 and 15 is curved inwardly in order to have the cylindrical projection 2 of the frame of the nailing machine fit 65 snugly against it and provide a firm support for the lower portion of the back of the support against the frame of the nailing machine.

Mounted to swing in the fork 11 is the horn 17 of the work support. This horn 75 is curved inwardly at the bottom to engage between the arms 14 and 15 of the fork 11. In this inwardly curved end of the horn 17 is provided a bearing 18 for the shaft 16 to pass therethrough and support the horn 80 17 in the fork 11. The bearing 18 is widened at each end thereof so that only a small portion in the middle of the bearing makes close circumferential contact with the shaft. This permits the bearing to rock so that 85 the horn can be rocked laterally for a limited distance. In addition to this lateral motion, the horn may also be swung outwardly away from the standard 10 as the bearing 18 permits a free swinging 90 movement of the horn in this direction. For the purpose of holding the horn in a normally central position, a spring 19 is stretched between the fork 11 and the horn 17. This spring is fastened to a stud 95 provided in the fork 11 and passes through a hole in the horn 17. A pin 21 passes through the loop on the outer end of the spring 19 on the outside of the horn in order to hold the spring in engagement with the horn. 100 The tension of the spring normally holds the horn in a central upright position so that when the horn is moved laterally to one side or the other, the spring pulls the horn back to its normal position on the 105 release thereof. This is also true when the horn is pulled forward away from the standard 10 in order to put one of the lasts on the support or take it off therefrom.

The lateral movement of the horn is essential because the nails must be driven into the heel of the shoe in a horse shoe shaped 110

formation near the periphery of the heel. Thus, the horn must be capable of moving to the left and right of the center of the heel as well as to the front and back thereof. This universal movement of the horn secured by the widened bearing 18 allows the horn to move in this horse shoe shaped path and hold the last with its shoe rigidly against the nailer.

10 As will be seen from an inspection of Fig. 1, the upper end of the horn 17 which carries the last of the shoe is bent so as to slightly slant away from the central axis of the standard 3. This is for the purpose 15 of holding the shoe and the heel to be fastened thereon at a slight angle to the nail driving mechanism so that the nails are driven into the heel at an angle. Owing to this angular alinement of the horn, the nails 20 are always driven toward the inside of the shoe which not only helps to fasten the heel more tightly to the shoe but also prevents the nails from being driven so that their points project out from the side of 25 the shoe and thus spoil either the heel or the sole to which it is to be fastened.

I claim:

1. In a work support for nailing machines, the combination of a shank, a fork 30 formed on the lower end of said shank,

said fork having a concave back adapted to rest against a convex upright, a shaft mounted in said fork, a horn, a bearing provided in said horn adapted to have said shaft pass therethrough, said bearing having a narrow, circular throat in the middle thereof and being widened at each end, said horn being adapted to rock laterally and swing forward and backward on said shaft in said fork.

2. In a work support for nailing machines, the combination of a shank, a fork formed on the lower end of said shank, a shaft mounted in said fork, a horn, a bearing provided in said horn adapted to have 45 said shaft pass therethrough, said bearing having a narrow, circular throat in the middle thereof and being widened at each end, said horn being adapted to rock laterally and swing forward and backward on 50 said shaft in said fork, said shank being of reduced diameter and having a series of holes therein and being adapted to engage a sleeve, and a pin adapted to engage in said holes above said sleeve to support said shank in said sleeve.

In testimony whereof I affix my signature.

ROBERT KONTEZKY.
